OF NEW YORK.

CIRCUIT-CONTROLLER.

1,322,431.

Specification of Letters Patent.

Patented Nov. 18, 1919.

Application filed August 20, 1918. Serial No. 250,732.

To all whom it may concern:

Be it known that we, EDWARD A. HALBLEIB and FRANK H. BANNER, citizens of the United States, residing at Rochester, in the 5 county of Monroe and State of New York, have invented certain new and useful Improvements in Circuit-Controllers; and we do hereby declare the following to be a full, clear, and exact description of the invention, such as will enable others skilled in the art to which it appertains to make and use the same.

This invention relates to electric circuit-controllers of the kind in which a circuit is 15 opened and closed by a reciprocating contact-member moving into and out of engagement with a relatively stationary contact-member.

In such devices the stationary contact-member is commonly mounted on the end of a screw-threaded shank, so that the contact-member may be conveniently adjusted to compensate for wear in the parts. The shank is threaded into an upright support, 25 which rises from, and is fixed to, the base-plate of the device.

In the manufacture of circuit-controllers as just described, some difficulty is found in accurately alining the contact-members so 30 that they will meet exactly face-to-face. An object of the present invention is to meet this difficulty, by the provision of a support, for the stationary contact-member, which is of such form that it may readily be bent in 35 various directions to make the necessary adjustments, but which is, at the same time, rigid with respect to the strains encountered in the operation of the circuit-controller.

Another object of the invention is to produce a support, for the stationary contact-member, which may be cheaply and easily formed from sheet-metal.

To the foregoing ends the invention consists in the circuit-controller hereinafter described, as it is defined in the appended claims.

In the accompanying drawings Figure 1 is a plan-view of a circuit-controller embodying the present invention. Figs. 2 and 50 3 are elevations of the support for the stationary contact-member. Figs. 4 and 5 are elevations of a modified form of the support for the stationary contact-member.

The invention is illustrated as embodied 55 in a circuit-controller such as is used in

connection with electric ignition-apparatus. Here the movable contact-member 10 is carried by a lever 11 which is oscillated, by the joint action of a cam 12 and a spring 13, so as to move the contact-member 10 into and 60 out of engagement with the stationary contact-member 14.

The stationary contact-member is mounted on a screw-threaded shank 15, and the present invention resides particularly in the 65 support in which this shank is fixed. This support is formed wholly of a single piece of sheet-metal, and, as shown in Figs. 2 and 3, it comprises a flat base-portion 16, and an upright portion 17 bent at a right angle to 70 the base-portion at one of the side-edges of the latter.

The upper end of the upright is bent and perforated to receive the shank 15 of the stationary contact-member. 75

This upper end may be formed in various ways, but in any case it is a feature of the invention that it be so formed that the shank 15 shall lie either in or parallel to the plane in which the width of the sheet-metal 80 lies in the upright 17. This arrangement has the great advantage that the support is rigid in the direction in which it is subjected to strain, while still sufficiently flexible in other directions to permit adjustment by bending the metal. 85

In Figs. 1, 2 and 3 the upper end of the upright is bent at a right angle so as to provide a short horizontal portion 18, and two lugs 19 are bent downwardly from the 90 edges of the portion 18. These lugs are perforated with alining screw-threaded holes, which receive the shank 15.

It will be apparent that lateral alinement of the contact-members may be secured by 95 bending the upright 17 laterally, while vertical alinement may be secured by bending the part 18 up or down. If the faces of the contact-members fail to meet squarely this may be corrected by twisting the upright 17. 100

An alternative form of construction is shown in Figs. 4 and 5. Here the hole for the reception of the shank 15 is produced by curling over the upper end of the upright to form a short horizontal sleeve 20, and the 105 inner surface of the sleeve is screw-threaded.

In previous circuit-controllers of the type in question a support has been provided, for the stationary contact-member, by bending a piece of sheet-metal at a right angle so as 110

to produce a horizontal base-member and an upright member, but in such cases the upright member has been perforated to receive directly the shank of the contact-member, 5 so that the upright was necessarily arranged with its width transverse to the shank. In this arrangement the sheet-metal is least adapted to sustain, without yielding, the force due to the hammering of the movable 10 contact-member against the stationary contact-member, so that if the metal be made thick enough to resist this force adequately, the metal is so rigid that the capacity for convenient adjustment by bending the metal 15 is largely or wholly sacrificed. In the construction hereinbefore described, on the other hand, comparatively thin and bendable sheet-metal may be used, consistently with any desired degree of rigidity to strain in a 20 direction longitudinal of the shank 15.

The invention claimed is:

1. In a circuit-controller comprising a movable contact-member, and a stationary contact-member having a screwthreaded 25 shank; a support, for the stationary contact-member, formed integrally of sheet-metal

and comprising a base; an upright in which the width of the metal is substantially in a plane parallel with the shank of the stationary contact-member; and a laterally-bent 30 portion, at the upper end of the upright, having a screw-threaded opening for the reception of said shank.

2. A support for the stationary contact-member of a circuit-controller, formed, as 35 in claim 1, in which a portion of the sheet-metal, at the upper end of the upright, extends in the form of two parallel lugs having alining openings to receive the shank of the stationary contact-member. 40

3. A support for the stationary contact-member of a circuit-controller, formed, as in claim 1, in which the sheet-metal, at the upper end of the upright, is bent first laterally to provide a substantially horizontal 45 portion, and then downwardly, from the front and rear edges of the horizontal portion, to provide two lugs, which are perforated to receive the shank of the stationary contact-member.

EDWARD A. HALBLEIB.
FRANK H. BANNER.
